UNITED STATES PATENT OFFICE.

CHRISTIAN F. HEINSS, OF CINCINNATI, OHIO.

AUTOMATIC SAFETY-STOP CLUTCH.

953,693.

Specification of Letters Patent.

Patented Apr. 5, 1910.

Application filed June 23, 1909. Serial No. 503,876.

To all whom it may concern:

Be it known that I, CHRISTIAN F. HEINSS, a citizen of the United States, and a resident of the city of Cincinnati, in the county 5 of Hamilton and State of Ohio, have invented certain new and useful Improvements in Automatic Safety-Stop Clutches, of which the following is a specification.

The several features of my invention and 10 the various advantages resulting from their use conjointly or otherwise will be apparent from the following description and claims.

In the accompanying drawings making a 15 part of this specification, and in which similar characters of reference indicate corresponding parts,—Figure 1 represents a side elevation of a portion of a punching machine, and of my newly invented mechanism combined therewith. Fig. 2 is a view 20 partly in section and partly in elevation of a portion of said machine. The section is taken in the plane of the dotted line 2, 2, of Fig. 1, and represents that face of the section and that part of the machine which 25 faces toward the right in Fig. 1, after all that mechanism which is at the right of said section line 2, 2, has been removed. Fig. 3 represents, on a smaller scale, a side elevation of the machine similar to that shown in 30 Fig. 1, but showing the clutch locked, and the roller plunger out of engagement with the adjacent cam. A portion of the large gear wheel seen at the right in Fig. 1 is partly broken away. Fig. 4 is a side view, 35 partly in elevation and partly in section of a portion of a punching machine, and also in combination therewith, the said mechanism constituting my improvement,—said mechanism being partially modified. Fig. 40 5 is a similar view, on a smaller scale of the mechanism shown in Fig. 4, but illustrating another working position of the parts.

A indicates a portion of the frame of the machine. Power is communicated to the 45 machine by a rotatory mechanism.

In the present illustrative instance, B indicates a gear wheel driven by a pinion (not shown) rotated by power. This gear wheel B is concentrically mounted loosely on a 50 crank shaft B². This crank shaft B² extends through the frame A, and at the other end of the machine operates a punch or equivalent reciprocating mechanism. As such a punch or other reciprocating mechanism is

well known and does not directly constitute 55 a part of my invention, any pictures of the same are omitted.

The clutch piece D is of a cylindrical form and has the usual projecting parts C, C, separated by depressions such as C². This 60 clutch piece D is mounted concentrically on the crank shaft B², and can slide along the said shaft in the direction of its length, but the shaft and it must and do always revolve together, because this clutch D and this shaft 65 B² are connected by the well known device termed a "feather". The counterpart clutch piece B³ has the usual projecting parts C³, separated by depressions C⁴. This latter clutch piece B³ is connected so as to 70 rotate with the gear wheel B.

On the rotatable piece D is a double cam E, F. The cam E has, referring to its working edge, a long straight portion E², and on each end of this long straight portion E² 75 an inclined portion E¹, and these portions E³ terminate in the straight portion E⁴. The cam F has, on reference to its working edge, a long straight portion F². The respective ends of this portion F² terminate 80 respectively in the inclined portions F³, and these terminate in the straight portion F⁴. The working face of cam F is, as shown, preferably in general conformation, like 85 that of cam E, but the faces F³, F² and the face F⁴ preferably extend farther from the plane of the face F². The cam E is here shown in one piece with the cam F, but the two cams may be separate. The double cam 90 E, F, encircles the clutch piece D, and is either attached thereto, or it may be integral therewith, as shown.

In the machine is located a slidable shaft M, against which a coiled spring N is adapted to abut. This spring N is shown 95 by dotted lines in Fig. 1. One end of this spring is at the shoulder M² of the shaft M, and the other end is against the end A³ of the pocket A² in this frame A. An extension or continuation M³ of the shaft M 100 is preferably present, and extends through the spring N, and through a bearing A⁵ at the left hand end of the pocket A². The place where the said shaft goes through said bearing is shown by dotted lines. This 105 bearing keeps the shaft M in alinement. In the preferred construction, and as a safe guard and lock, I construct this pocket so

that it is slideable. This can be simply accomplished, by making it separate from the main frame A. The pocket can slide upon the shaft M³. The spring N fills the pocket, 5 and the shaft M³ extends through the center of this coiled spring N. Therefore the spring N in the pocket and the latter can readily slide upon the shaft M³, and vice versa, the shaft M³ can slide within the said 10 pocket and spring.

I provide a lever R, and connect to it a handle lever R². I pivot one end of this lever R to a stationary part of the frame or machine. In the present illustrative instance, I pivot it by a suitable pivot R³, to the bearing piece A⁵. To the other end of the lever, I pivot by the connection R⁴, a link R⁵, and the other end of this link R⁵ I pivotally connect by a connection R⁶ to 20 the side of the pocket A². The shoulder M² aforesaid is of a diameter small enough to be capable of entering that recess in the pocket A² in which the spring N is located.

The forward journal bearing for the shaft 25 M is preferably as follows: It consists of a bracket piece P bolted to the adjacent frame A by bolts P², P². Fixed to the shaft M and extending through a slot M⁶ in the piece P is a stud M⁵, which in order 30 to avoid friction in its contact with the key or stop bar G⁴ hereinafter specified, is provided with a roller M⁴, which is rotatable on said stud M⁵. The shaft M extends still farther to the right and at its end portion 35 is provided with a friction roller M⁷, adapted to bear against the surface of the said cam F. When the lever R, R² is in the position shown in Fig. 1, the pocket A² and its spring are retracted, and exercise no 40 function. When the lever R, R² is placed in the position shown in Fig. 3, the pocket A² and the spring N within it is moved forward and this spring is compressed against the shoulder M² of the shaft M, and 45 the latter enters, and for the time being occupies the forward part of the recess in the pocket A². The resiliency of the spring N is thus put into use, and the elasticity of the spring N tends to move the clutch piece 50 D toward the counterpart clutch member B³, and cause the clutch piece D to engage the counterpart clutch member B³, and will always do so, when permitted as hereinafter specified.

Preferred mechanism for allowing the clutch piece D of the clutch to engage the clutch member B³, and also for disengaging the said clutch piece D from the clutch member B³ and to lock the parts so that the 60 clutch cannot again operate until an intentional and new act through human agency has taken place, is as follows:—A vertical bar G, having its upper portion angulated or curved extends through guides H, H, the 65 latter preferably formed of recesses in the

frame A in which recesses the shaft G lies, the shaft being held to place in these recesses by cross bars respectively marked H², the latter held in position by the bolts H³, screwed into the frame A. The upper end 70 of the shaft is connected to the vertically slideable plunger G², which latter extends through a passageway in the frame extension A⁴, and can move up and down therein. That end of this slideable plunger G² which 75 is next the clutch piece D, has a roller X rotatory upon a reduced end portion G² R of this plunger, and held in place by a suitable device, as the screw X² shown by dotted lines in Fig. 1. Against this roller X the 80 cam E moves when the plunger G² is in front of the roller X. When the clutch piece D is drawn back out of engagement, the bottom portion of the plunger G² will be in front of the cam E, as shown in Fig. 1. 85 The vertical shaft G can be elevated at will by the operator. The means for this purpose will consist of a suitable lever worked by the hand or by the foot. In the present illustrative instance, this shaft is preferably 90 elevated by the more common means, to wit: a treadle. The latter being well understood, a picture of it is omitted. On this shaft G, a stop G³ is located. This stop G³ when the shaft G is elevated, strikes a stationary 95 abutment, preferably the lower cross bar H², and this latter prevents any farther elevation of the shaft G and of the plunger G² which it carries.

Mechanism for securely locking the clutch 100 member D, when the latter is out of engagement with the clutch part B³, and thus preventing the possible engagement of these two opposite clutch members, when the operator has not put these into engagement is 105 as follows: On the shaft G is fixed a key or stop bar G⁴, and this stop bar rises and falls with the shaft G. This stop bar should, on the lower left hand corner portion, be rounded for diminishing the friction between it and the roller M⁴. On the reciprocating shaft M is the said stud M⁵ carrying the roller M⁴, and this stud M⁵, as before indicated, is movable with said shaft M 110 back and forth in the slot M⁶ of the frame A. The friction roller M⁷, which is located on the forward end of this shaft M, is placed so as to be in contact with the face 115 of cam F, F², F³. The lower corner of that end of the slideable key bar G⁴ being rounded as aforementioned, then, after being with the shaft G elevated (as shown in Fig. 3), then when it with said shaft descends—it readily presses back the roller stud M⁴, M⁵, and assumes the position shown in Fig. 1. 120

The mode in which the already described mechanism operates is as follows:—The mechanism being in the position shown in Fig. 1, the power wheel B is put in motion by connecting it to a motor power already 125

in motion. The clutch member B^3 is now also rotating with the gear wheel B. Whenever the operator desires the punch of the machine to descend, he moves the lever R, R^2 5 into the position it occupies in Fig. 3. He then depresses the treadle and elevates the shaft G, which latter lifts the roller stud G^2R out of contact with the cam E. At the same time, the elevation of the shaft G has 10 lifted the key bar G^4 out of contact with the roller stud M^4 , M^5 . The spring N is now free to move the shaft M and does move it toward the clutch, and advances the clutch piece D into engagement with the clutch member B^3 . The parts immediately concerned in this invention are now in the position shown in Fig. 3. The shaft B^2 is now 15 in rotation and will operate the punch or other mechanism at the other end of the machine. As soon as the operator has elevated the shaft G and the engagement of the two parts of the clutch has been effected, the operator removes his pressure on the treadle and allows the shaft G to drop. The stud 20 G^2 will then descend and as permitted by the cam E, will rest upon the smooth peripheral surface of the clutch D. As the cams with the piece D rotate, the cam E^2 impinges against the roller plunger G^2 , and 25 as the latter does not yield laterally, the clutch D is forced toward the left hand of Fig. 1, and the clutch piece D is moved out of connection with the clutch member B^3 , and the shaft B^2 ceases to turn and the 30 upper lifted punch or the like will not again descend until the operator works the treadle. As the clutch D is pushed back as last aforementioned, the cam F^3 will move the roller M^7 to the left, which moves the shaft M and 35 the roller M^4 to the left, and at the same time compresses the spring N, thereby permitting the key bar G^4 to descend behind (to the right of) this stud M^4 into the position shown in Fig. 1. Then the clutch piece 40 D (C^1 , C^2) is securely prevented from moving into engagement with the clutch member B^3 (C^3 , C^4) until the shaft G is intentionally elevated by human agency. Because, although, through wear, the plunger 45 G^2 , X (should the spring be allowed to act) may be not quite far enough to the left to force the cam E and the clutch D at all times far enough away from the clutch part C^3 , C^4 , to prevent the clutch part C, C^2 50 from engaging with it, nevertheless the cam F^3 being higher than the cam E^3 the key bar G^4 will keep the stud M^5 , M^4 to the left and with it hold the spring N from acting 55 upon the mechanism, and thus the opposite faces of the clutch cannot at all engage. In 60 this way, the mechanism is safe-guarded.

A modified construction of the parts already described is illustrated in Figs. 4 and 5. In this construction, the shaft G which 65 is connected to the treadle or other means

for moving it, is drawn down when the machine is to be started. The plunger G^2 is preferably located in the arm or extension A^4 of the frame. Here this extension A^4 is simply located below the clutch D. 70 In this extension A^4 there is a lever G^8 , pivoted to the extension at G^9 . The upper end of this lever carries a roller G^7 , rolling against the cam F, F^2 , F^3 , substantially as does the roller stud G^7 in Fig. 1. This 75 lever, at a part of it, below this roller stud is adapted to impinge against the rounded end M^8 of the shaft M. The shoulder M^2 of the shaft M impinges against the spring N as heretofore mentioned. The lower end 80 of this lever G^8 is rounded at G^{10} , as shown. The plunger G^2 carries an arm G^{12} , suitably secured to the stud, preferably by the portions of the arm G^{12} embracing the plunger G^2 and then set in place by the set screw 85 G^{13} , which is screwed through this arm G^{12} and against the plunger G^2 . The outer end of the arm G^{12} carries an end portion G^{14} angulated upward and adapted to be at the left of the lever G^8 when the upper end of 90 the lever is against the part F^3 of the cam F. The operation of this modified mechanism is as follows: The parts being in the position shown in Fig. 4, to start the machine, after wheel B is in rotation, the operator 95 depresses the shaft G, and withdraws the roller plunger G^2 from engagement with the cam E. The compressed spring N now, through the agency of the shaft M, presses the lever roller G^7 against the cam F^3 and 100 moves the clutch piece D toward the gear wheel B, and puts the clutch part C, C^2 into engagement with the parts C^3 , C^4 of the clutch member B^3 and rotates the mechanism which operates the punch. The operator 105 now allows the shaft G to rise, which carries up the plunger roller G^2 against the clutch D. As the cam E, E^2 , E^3 rotates, it, by impinging on said plunger G^2 , forces the clutch D to the left and disengages the 110 clutch. As the cam rotates, the cam F^2 , F^3 moves the roller G^7 and the lever G^8 moves the shaft M back and compresses the spring N. The lower end portion G^{10} of the lever 115 is now in a position where the angulated end G^{14} of the arm G^{12} can move to the left of this end portion G^{10} , and it does so move and then locks the lever G^8 so that it is immovable until the shaft G is again moved by human agency. Thus the spring is prevented 120 from acting, and there is nothing which can tend to unite the disengaged parts of the clutch. Thus the disengagement of the clutch is made continuously secure and is safe-guarded. 125

It is to be noted that, in the construction illustrated in Figs. 4 and 5, the portions E^2 , E^3 , E^3 of the one cam are respectively a quarter of a circle in advance of those portions F^2 , F^3 , F^3 of the other cam. Therefore 130

- the clutch is disengaged, before the spring is pressed back and locked in an immovable position. When the operator has finished using the machine, he moves back the lever 5 R, R^2 into the position shown in Fig. 1. The primary function of this lever R, R^2 , and the construction which renders the pocket A^2 and the spring N slideable, consists in preventing any possible operation of 10 the machine while the operator is putting in a new die, or the like. Such unexpected operation of the machine would be dangerous, and likely to result in loss of hand, limb, or of life itself.
- 15 The construction of the pocket A^2 with spring N so as to be slideable, and of the lever R, R^2 , is obviously applicable to the mechanism shown in Figs. 4 and 5, but as it is not the main feature of my invention, and 20 I desire to illustrate the operation of the mechanism where the lever R, R^2 and the slideability of the pocket is omitted, I have not shown the said lever and pocket as slideable, in Figs. 4 and 5.
- 25 In Fig. 1, in case the lever R, R^2 were omitted, the pocket A^2 with spring N would be stationary, but the spring N would always be in active resilient contact with the shoulder M^2 of the shaft M .
- 30 What I claim as new, and of my invention and desire to secure by Letters Patent, is:—
1. In a machine for operating on material by an intermittent movement, a clutch having a reciprocatory member, two cams in connection with said member, a reciprocatory plunger, mechanism for reciprocating the latter, one of the said cams being adapted to operate against the plunger when the latter is within reach of the cam, a spring, and a shaft advanced by the spring, means for enabling said spring actuated shaft to operate against such second cam and operate the said clutch member, a stop bar or key 35 in connection with the reciprocating mechanism for operating the plunger, and adapted to lock the spring from acting on the adjacent cam and its said clutch member.
2. In a machine for operating on material 40 by an intermittent movement, the combination of a clutch, having a reciprocatory member, two cams in connection with the latter, a reciprocatory plunger, a plunger shaft connected to the plunger for reciprocating the latter, one of said cams being adapted to operate against the plunger, when the latter is positioned for moving the movable clutch member out of engagement with the opposite clutch member, a 45 spring, and a shaft advanced thereby, the shaft adapted to operate against the second cam and advance the movable clutch member into engagement with the opposite clutch member, a stop bar, in connection 50 with the plunger shaft and adapted, when the first named cam has retracted the movable clutch member to hold back the spring shaft, and prevent the spring from operating to close together the clutch members.
3. In combination, the clutch having a 55 movable member, a reciprocatory plunger adapted to come into proximity with the movable clutch member, a reciprocatory shaft connected to this plunger, a cam on the movable clutch for operating in connection with the plunger and retracting the movable clutch piece, a spring, and a shaft advanceable by the spring, the forward end of this shaft provided with a roller, in contact with the face of the second cam, the 60 said spring shaft carrying a stud, the reciprocatory plunger shaft carrying a stop bar which, when the plunger in coöperation with the first named cam has retracted the movable clutch member, is interposed against the said stud and holds back the spring and spring shaft.
4. In combination, the clutch having a 65 movable member, a reciprocatory plunger adapted to come into proximity with the 70 movable clutch member, a reciprocatory shaft connected to this plunger, a cam on the movable clutch for operating in connection with the plunger and retracting the movable clutch piece, a slideable pocket or 75 receptacle, a spring located therein, a shaft adapted at one end to bear against the face of the second cam, an abutment of the shaft in proximity to the spring, a lever, and a link connecting the lever to the sliding 80 spring pocket, for enabling the lever when operated to advance the spring against the abutment of the shaft and resiliently press the shaft forward for advancing the movable clutch member into engagement with 85 the opposite member of the clutch, a stop bar or key on the reciprocatory shaft for 90 moving the plunger, which when the movable clutch member has been moved out of engagement with the opposite clutch member, 95 and the spring shaft has been retracted, 100 shall engage the spring shaft and hold it back from operating to move the movable clutch member into engagement with the opposite member of the clutch.
5. In combination with a clutch and two 105 cams in connection with the movable member of the clutch, and a reciprocatory plunger, for operating the first named cam, and disengaging the members of the clutch, and a shaft, which when advanced shall operate 110 against the second cam to advance the movable clutch member into engagement with the clutch, and a stop bar or key, for locking the movable clutch when the latter has been retracted, the device consisting of the slideable spring carrier, and a spring carried 115 thereby, and the abutment on the shaft for the spring to impinge when the latter is advanced, and a lever pivoted to a stationary support, and a connection between the lever 120 and the plunger shaft.
6. In combination with a clutch and two cams in connection with the movable member of the clutch, and a reciprocatory plunger, for operating the first named cam, and disengaging the members of the clutch, and a shaft, which when advanced shall operate 125 against the second cam to advance the movable clutch member into engagement with the clutch, and a stop bar or key, for locking the movable clutch when the latter has been retracted, the device consisting of the slideable spring carrier, and a spring carried thereby, and the abutment on the shaft for the spring to impinge when the latter is advanced, and a lever pivoted to a stationary support, and a connection between the lever 130 and the plunger shaft.

and the said lever when operated in one direction to advance the spring against the abutment of the said shaft, and through the agency of the second cam, cause the clutch members to engage one another, and when operated in the opposite direction to retract the spring out of engagement with the said shaft.

6. In combination, the clutch having a
10 movable member, a reciprocatory plunger
adapted to come into proximity with the
movable clutch member, a reciprocatory
shaft connected to this plunger, a cam on
the movable clutch for operating in con-
15 nection with the plunger and retracting the
movable clutch piece, a spring, and a shaft
advanceable by the spring, the forward end
of this shaft provided with a roller, in con-
tact with the face of the second cam, the
20 said spring shaft carrying a roller stud, the
reciprocatory plunger shaft carrying a stop
bar, which when the plunger in coöperation
with the first named cam has retracted the
movable clutch member is interposed against

the said roller stud and holds back the spring 25 and spring shaft.

7. In combination, the clutch having a movable member, a reciprocatory plunger adapted to come into proximity with the movable clutch member, a reciprocatory shaft connected to this plunger, a cam on the movable clutch for operating in connection with the plunger and retracting the movable clutch piece, a spring, and a shaft advanceable by the spring, the forward end of this shaft provided with a roller, in contact with the face of the second cam, the said spring shaft carrying a roller stud, the reciprocatory plunger shaft carrying a beveled stop bar, which when the plunger in co-operation with the first named cam has retracted the movable clutch member is interposed against the said roller stud and holds back the spring and spring shaft. 30 35 40
